No. 12,610

Dec. 20, 1881

UNITED STATES PATENT OFFICE.

H. CLAY BASCOM, OF TROY, AND TOBIAS S. HEISTER, OF LANSINGBURG, NEW YORK, ASSIGNORS TO N. S. VEDDER PATTERN WORKS, BASCOM, GALBRAITH & CO., OF TROY, NEW YORK.

DESIGN FOR A STOVE.

SPECIFICATION forming part of Design No. 12,610, dated December 20, 1881.

Application filed November 21, 1881. Term of patent 7 years.

To all whom it may concern:

Be it known that we, H. CLAY BASCOM, a citizen of the United States, residing in the city of Troy, in the county of Rensselaer and State of New York, and TOBIAS S. HEISTER, a citizen of the United States, residing in the village of Lansingburg, in said county and State, have jointly invented and produced a new and original Design for Cooking Stoves, of which the following is a specification, reference being had to the accompanying cut, print, or engraving of a stove having said new design.

The design for the panel-ornament A consists of the elliptical beveled outer part, b, bordered along its inner edge by the fillet c inclosing the field d, having therein the bow e, quiver f, opposite semi-rosettes g, leaves h, and linear broken leaves i, all shaped and combined substantially as shown in the accompanying print.

The design for the outer portion of the panel H consists of the two diagonally-opposite corner ornaments, j k, with the plant-form ornaments l on the high rear part, and the compound scroll-and-arrow ornament m on the low forward part, all shaped and arranged substantially as shown in the accompanying engraving.

The design for the oven-door I consists of the compound ornament A, composed as above described, in combination with the panel H, ornamented as above specified, and the outer ornamental border, n, all shaped and arranged substantially as represented in the aforesaid cut.

The design for the small doors or plates O P consists of the ornamental border q inclosing

the panel surface r, having the central compound bow, quiver, and shield ornament s, and corner ornament, t, with plant ornaments u, all shaped and arranged substantially as shown 40 in the aforesaid engraving.

The design for the legs consists of the representations of pinnate leaves v, alternating with linear leaves w on the swelled surface x, bordered by ornamental edge fillets y, all shaped 45 and arranged substantially as shown in the accompanying print.

What we claim as our joint invention is—

1. The design for the panel ornament A, composed of the parts b c d e f g h, all shaped 50 and combined as set forth.

2. The design for the outer portion of the panel H, consisting of the parts j k l m, all shaped and arranged as set forth.

3. The design for the oven-door I, consisting 55 of the compound ornament A, panel H, having the outer ornamental border n, all combined as set forth.

4. The design for the small doors or plates O P, composed of the parts q r s t u, all shaped 60 and arranged as specified.

5. The design for the legs, consisting of the parts v w x y, all shaped and arranged as set forth.

In testimony whereof we hereunto set our 65 hands, in the presence of two subscribing witnesses, this 18th day of November, 1881.

H. CLAY BASCOM.
TOBIAS S. HEISTER.

Witnesses:

AUSTIN F. PARK,
JAMES T. GOODFELLOW.
